TENSION RELEASE MECHANISM FOR SEWING
MACHINESStanley J. Ketterer, Morris Plains, N.J., assignor to The
Singer Manufacturing Company, Elizabeth, N.J., a corporation of New JerseyFiled Aug. 24, 1961, Ser. No. 133,604
3 Claims. (Cl. 112—181)

This invention relates to lock stitch sewing machines of the type in which locking or bobbin thread is replenished automatically during a continuation of the same interrelated motion of the needle and the loop-taker as is required for the formation of lock stitches, and more particularly to a novel means for rendering ineffective the locking or bobbin thread tensioning means during the thread replenishing operation.

It is an object of this invention to provide a means for releasing the under or bobbin thread tensioning means during introduction and replenishment of a thread on a bobbin in place in a loop-taker so as to provide for the smooth flow of thread thereto with a minimum of stress thus reducing the possibility of thread breakage.

It is also an object of this invention to provide a novel under or bobbin thread tension releasing means which is compact, simple, and economical in construction and which does not interfere with the operation of the thread replenishing mechanism.

In the accompanying drawing of a preferred embodiment,

FIG. 1 represents a vertical cross-sectional view of a sewing machine loop-taker having this invention applied thereto and including a fragment of the work support and the needle and illustrating the relative position of parts during introduction and replenishment of bobbin thread.

FIG. 2 represents a vertical cross-sectional view of a sewing machine loop-taker similar to FIG. 1 but illustrating the relative position of parts during the subsequent sewing operation.

FIG. 3 represents a front elevational view of the loop-taker of FIGS. 1 and 2.

FIG. 4 represents a top plan view of the bobbin case, and,

FIG. 5 represents a perspective view of the thread tensioning spring of this invention.

This invention is an improvement of the construction disclosed in the copending United States patent application of Stanley J. Ketterer and William J. Edwards, Serial No. 15,955, filed March 18, 1960. This copending application may be referred to for the details of construction of the loop-taker, particularly with regard to the means for introducing and replenishing a supply of under or locking thread to the bobbin and thereafter forming a lock stitch using the replenished bobbin thread supply.

In the accompanying drawing, the sewing machine work support, as indicated at 11, is fitted with a throat plate 12 having an aperture 13 through which passes an endwise reciprocable thread carrying needle 14. Journaled beneath the work support is a hollow loop-taker drive shaft 15 to which is fixed a loop-taker indicated generally as 16. The loop-taker is formed with a cup-shaped body portion 17 formed with a gap 18 and at one side of the gap with a needle loop seizing beak 19. The cup-shaped body portion of the loop-taker is formed internally with an annular raceway 20 in which is journaled by means of a bearing rib 21, a bobbin case 22. The bobbin case is formed with a notch 23 which accommodates a rotation restraining finger 24 fixed relatively to the work support, thus to prevent

2

rotation of the bobbin case with respect to the loop-taker. The bobbin case 22 is formed with a stud 25 disposed substantially co-axially of the loop-taker drive shaft 15 and internally threaded to accommodate a headed screw 26. Journaled freely on the stud 25 is a bobbin member 27 which is constrained for limited sliding movement axially of the stud by the headed screw 26.

The loop-taker is preferably operated in timed relation with the needle two revolutions for each needle reciprocation and in a timed relationship such that the loop-taker beak 19 will pass adjacent to the needle during each work penetration thereof for seizure of needle thread loop whenever a loop of thread is presented by the needle. Such interrelated motion of the needle and loop-taker is termed stitch forming motion and it will be understood that the same stitch forming motion of the needle and loop-taker occurs during bobbin thread replenishment even though no stitches will be formed during the replenishing period.

Referring to FIG. 4, a gap 30 is formed in the bobbin case bearing rib 21 providing an ingoing pocket 31 on that side of the gap toward which the loop-taker turns, against which pocket loops of thread seized by the loop-taker beak 19 are directed in the normal handling of thread loops by the loop-taker. During the sewing operation when a free space exists behind the bobbin and bobbin case as illustrated in FIG. 2, the loops of thread which are carried into the ingoing pocket by the hook beak are free to slide about the bobbin case, one limb across the exposed face and one limb through the free space behind the bobbin case. During sewing, the portion of the loop which is initially trapped in the ingoing pocket thus gradually slides across the gap 30 in the bobbin case bearing rib and is positioned at the opposite side of the gap 30, which is termed the outgoing pocket 32, as the thread is drawn from the loop-taker and set into the work.

Referring to FIGS. 1 and 2, 40 indicates a bobbin winding member carried within the cup-shaped loop-taker body and interlocked for rotation with the loop-taker. The bobbin winding member is fast on a rod 41 shiftable axially within the hollow loop-taker drive shaft 15. By means of a control mechanism (not shown) which may be in the form of a cam means as described in the above referenced patent application No. 15,955, the rod 41 may be shifted to position the bobbin winding member into engagement with the bobbin member 27 as illustrated in FIG. 1, in which position thread will be replenished on the bobbin. After the bobbin thread supply has been replenished, the rod 41 is shifted to the right as viewed in FIG. 2 to shift the bobbin winding member away from the bobbin member thus readying the loop-taker for the formation of stitches.

A leaf spring 42 carried on the loop-taker body portion extends in spaced relation behind the loop-taker beak 19 and is engaged by a thread gripping arm 43 on the bobbin winding member 40 when the bobbin thread is to be replenished so as to grip on the hook 60 a loop of needle thread seized thereby. The bobbin winding member is formed with a rim 44 which, as illustrated in FIG. 1, envelops the bobbin member when the bobbin winding member is shifted into engagement therewith. The movement to the left of the bobbin winding member during bobbin thread replenishment shifts the bobbin member axially along the stud 25 as illustrated in FIG. 1, and a pin 45 on the bobbin winding member engages a notch 46 in the bobbin member to provide for a positive drive of the bobbin member.

When the bobbin winding member is shifted into the position illustrated in FIG. 1 for replenishment of the bobbin thread supply, the free space behind the bobbin

case is closed, and the thread loop carried by the loop-taker beak into the ingoing pocket 31 is constrained therein. An L-shaped thread guided slot is formed in the bobbin case having a limb 50 extending from the ingoing pocket 31 and a limb 51 extending across the face of the bobbin case through which slot the thread is directed as it is introduced to the bobbin. Secured to the bobbin case as by screws 52 is a thread tensioning spring 53 having a free extremity 54 disposed in the limb 51 of the thread accommodating slot. The free extremity of the thread tensioning spring is biased against one wall of the limb 51 of the thread accommodating slot as illustrated in FIG. 2 so to apply a frictional resistance to the passage of thread to or from the bobbin to the work. A finger 55 is formed on the free extremity 54 of the thread tensioning spring, which finger extends, as illustrated in FIGS. 1, 2 and 3, into the axial projection of the bobbin member 27 such that upon axial sliding movement of the bobbin along the stud 25 when engaged by the bobbin winding member 40, the bobbin member will engage the finger 55 and shift the thread tensioning spring away from that edge of the thread guiding slot toward which it is biased. With this construction, therefore, during introduction and replenishment of thread to the bobbin, the bobbin thread tensioning means will be rendered ineffective and the smooth flow of thread thereto will be unimpeded, thus minimizing the possibility of thread breakage. The tension will be automatically reapplied when the parts are shifted into position for sewing.

In FIG. 1, in which the parts are illustrated in a position for bobbin thread replenishment, the loop-taker beak 19 is illustrated in a position in which it has seized a loop of needle thread T^a. The bobbin thread tensioning spring 53, as illustrated in this figure, is held in an ineffective position for introduction and replenishment of the bobbin thread free of any effect of the tensioning means.

In FIG. 2, the loop seizing beak 19 of the loop-taker is similarly illustrated in a position seizing a loop of needle thread T^a and the thread which had previously been replenished on the bobbin is indicated at T^b, under the influence of the bobbin thread tensioning spring 53.

Having thus set forth the nature of this invention, what I claim herein is:

1. A lock stitch sewing machine having a frame including a work support, an endwise reciprocatory thread carrying needle carried by said frame at one side of said work support, a loop-taker journaled for turning movement in the frame at the opposite side of said work support, means for imparting interrelated motion to said needle and said loop-taker as is required for the formation of lock stitches, a bobbin case journaled in said loop-taker, means carried on said frame for constraining said bobbin case from turning movement with said loop-taker, a bobbin journaled in said bobbin case for turning and limited axially sliding movement therein, a

thread tensioning spring anchored on said bobbin case and having a free extremity biased yieldingly against said bobbin case, means effective during said interrelated motion of said needle and loop-taker as is required for the formation of lock stitches for introducing a thread between the free extremity of said thread tensioning spring and said bobbin case and to said bobbin, bobbin winding means including a bobbin rotating member shiftable in a direction axially of said bobbin into effective driving engagement therewith and effective during continued interrelated motion of said needle and loop-taker as is required for the formation of lock stitches for winding on said bobbin said thread introduced thereto, and means operated by said bobbin winding means for shifting the free extremity of said thread tensioning spring away from said bobbin case during operation of said means for introducing thread to said bobbin and during operation of said bobbin winding means.

2. A mechanism as set forth in claim 1 in which said means for shifting the free extremity of said thread tensioning spring away from said bobbin case comprises a finger carried by said thread tensioning spring and disposed in the path of axial sliding movement of said bobbin at the opposite side of said bobbin from said bobbin rotating member.

3. A loop-taker for a lock stitch sewing machine comprising a rotatable cup-shaped loop-taker body formed with a gap, a loop seizing beak carried by said loop-taker body and projecting into said gap in the direction of rotation of said loop-taker body, said loop-taker body being formed with an annular internal groove defining a raceway, a non-rotating bobbin case formed with a cavity, a bearing rib formed on said bobbin case and journaled in the raceway in said loop-taker body, said bearing rib being formed with a gap, one edge of said gap in said bobbin case bearing rib toward which said loop-taker body rotates defining an ingoing thread pocket, a bobbin journaled in said bobbin case for turning and limited axial sliding movements therein, a thread guiding slot formed in said bobbin case open to said bobbin case cavity and leading from said ingoing pocket, a thread tensioning spring means carried by said bobbin case and yieldingly bearing against one wall of said thread guiding slot, and a finger formed on said thread tensioning spring means and extending into the path of axial sliding movement of said bobbin for shifting said thread tensioning spring means away from said one wall of said thread guiding slot upon axial shifting of said bobbin.
